UNITED STATES PATENT OFFICE.

GEORGE W. BLAKE, OF WYANDOTTE, MICHIGAN.

POURING-SPOUT.

1,118,626.

Specification of Letters Patent.

Patented Nov. 24, 1914.

Application filed September 27, 1913. Serial No. 792,104.

To all whom it may concern:

Be it known that I, GEORGE W. BLAKE, a citizen of the United States of America, residing at Wyandotte, in the county of Wayne and State of Michigan, have invented certain new and useful Improvements in Pouring-Spouts, of which the following is a specification, reference being had therein to the accompanying drawings.

This invention relates to a pouring spout for a package and more especially to an arrangement thereof whereby the contents of a package may be readily discharged as it is needed and the package resealed without the use of implements, the spout forming a closure for a delivery opening of the package, and also providing a discharge trough that is best adapted to prevent lodgment of material passing thereover.

The invention consists in the matters hereinafter set forth and more particularly pointed out in the appended claims.

In the drawings, Figure 1 is a view of an upper portion of a package provided with a spout that embodies features of the invention; Fig. 2 is an enlarged view of a transverse section through the upper portion of the spout and receptacle, showing the spout in its closed position; Fig. 3 is a similar view showing the spout in open position; Fig. 4 is a view in detail of the opening in the receptacle, with a section line II-II thereon that indicates the point where the views shown by Figs. 2 and 3 are taken. Figs. 5 and 6 are views in section and in detail, enlarged, showing the adaptation of a spout to a different form of receptacle; Fig. 7 is a plan view in detail of the modification; and Fig. 8 is a view in perspective of the spout removed.

Referring to the drawings, a receptacle 1 has a substantially triangular opening with depending apex as indicated at 2 in Fig. 4, an inset flange 3 being preferably formed around the opening, one section of which has a longitudinal hinge slot 4. The hinge portion of the flange is interrupted to form a pouring gap 5 at the lower apex of the opening 2. A V shaped pouring trough has one side 6, a cover side that conforms to the contour of the shoulder formed by the inset flange 3 so as to rest in the recess thus made in overlapping relation to the flange. A suitably arranged hinge tongue 7 of any preferred shape engages the slot 4 whereby

the side 6 may be swung in and out of contact with the side of the receptacle. Preferably the side 6 is formed to constitute a substantially flush continuation of the side of the receptacle on which it rests. Along the margin of the side 6 opposite that on which the tongue 7 is formed, the side is infolded against itself so that the resultant tongue 8 bears against the flange while an inner portion 9 forms a free side that corresponds in shape substantially to the outline of the opening 2, projects when the spout is closed, into the interior of the receptacle. At its inner edge a marginal flange 10 acts as a lock to prevent withdrawal from the casing. The side 9 is conoidal with the hinge pivot as its axis so that it is always in frictional engagement with the contiguous margin of the opening. In order that the spout may be locked when closed, the inset bend or groove 12 is formed at the angle between the flange 8 and side 9 into which the margin of the body snaps when the spout is closed. The upper margin 13 of the side 9 is also curvilinear with its center of motion at the lower corner of the trough so that it bears upwardly against the upper margin 14 of the opening. A finger pull 15 is formed on the side 6 and may if desired be arranged to bend over the upper edge of the receptacle 1 so that when the package is ready for shipment a label may be pasted over the closed spout and may be readily turned by inserting a finger nail under the finger pull 15 and drawing the spout out or the finger pull may extend laterally.

In Figs. 5, 6 and 7 modifications of the invention whereby the spout may be made adaptable to a flat walled receptacle, are shown. In such construction, the cover side is merely made to conform to the wall against which it closes.

In operation the spout when closed forms a hermetrical seal for the package. When open it provides a V shaped trough through which granular substances readily pass. The interruption of the slotted flange of the opening at the apex of the latter effectively prevents the lodgment of anything in the spout when the latter is being moved back into closed position, such material falling back into the body of the receptacle.

Obviously, changes in the details of construction may be made without departing

from the spirit of my invention and I do not care to limit myself to any particular form or arrangement of parts.

What I claim is:—

- 5 1. The combination with a receptacle having a triangular pouring opening in the wall thereof, one of the margins thereof being cut away at the angle of the opening and having a hinge slot parallel to the major
- 10 portion of its length, of a two sided pouring spout having a cover side, a hinge member formed on the cover side engaging the hinge slot, and a free side extending from the outer margin of the hinge side in frictional
- 15 engagement with the contiguous side of the pouring opening, the cover side being adapted to overlap the margins of the opening when the spout is in closed position.
- 20 2. The combination with a receptacle having a triangular pouring opening in the receptacle, with inset margins around the opening and a hinge slot in the receptacle along one inset margin, of a two sided pouring spout with a cover side provided with a
- 25 hinged member engaging the slot and with margins that overlap the inset margins of the opening, and a side extending from the

free margin of the hinge side in sliding engagement with the contiguous margin of the opening, and having a longitudinal depression adjacent the hinge side the margins of the receptacle adjacent the latter side being adapted to engage the longitudinal depression in said side adjacent the overlying flange of the cover side. 35

3. A pouring spout for a receptacle having a triangular opening, comprising a cover side adapted to close over the opening and hinged to the receptacle along one side thereon, and a free side formed integrally along 40 the free edge of the cover side, with a flange on the other edge thereof limiting the outward movement of the spout in the opening, the free side being indented along the line of its connection with the coverside and 45 being adapted to yieldingly engage and hold the side of the opening in said indentation when the spout is in closed position.

In testimony whereof I affix my signature in presence of two witnesses.

GEORGE W. BLAKE.
